To all whom it may concern:

Be it known that I, Irving Cohen, a citizen of the United States and residing in Manhattan, in the city, county, and State of New York, have invented a new, original, and ornamental Design for a Coat, of which the following is a specification, reference being had to the accompanying drawing, forming part thereof.

My design is characterized by the fold, which follows the contour of the raglan sleeves in back and which continues straight in front as shown, in combination with the specific stitching on the shoulders. The flower cluster on the shoulder of the coat is permanently attached.

I claim:

The ornamental design for a coat substantially as shown and described.
